Int. Cl. D26—05
U.S. Cl. D48—23 R

FIG. 1

FIG. 2

FIG. 1 is a sectional view taken through the center of the lamp showing my new design.

FIG. 2 is a perspective view of a lamp showing my new design, the opposite side being a mirror image of the side shown, except for the electrical lead wire.

The lamp is shaded to indicate contrast.

The bulb, socket and cord are shown in broken lines for illustrative purposes only.

This is a continuation-in-part of Design Application Ser. No. D. 166,335, filed July 26, 1971, and now abandoned.

I claim:

The ornamental design for a lamp, as shown and described.
